UNITED STATES PATENT OFFICE.

PATRICK B. DELANY, OF SOUTH ORANGE, NEW JERSEY, AND LOUIS W. SHUMAKER, OF NEW YORK, N. Y., ASSIGNORS TO TELEPOST COMPANY, OF NEW YORK, N. Y., A CORPORATION OF MAINE.

APPARATUS FOR TREATING TELEGRAPH-TAPE.

1,350,789.

Specification of Letters Patent. Patented Aug. 24, 1920.

Application filed November 30, 1917. Serial No. 204,680.

To all whom it may concern:

Be it known that we, PATRICK B. DELANY, a citizen of the United States, residing at South Orange, in the county of Essex and 5 State of New Jersey, and LOUIS W. SHUMAKER, a citizen of the United States, residing at New York, in the county of New York and State of New York, have invented certain new and useful Improvements in Apparatus for Treating Telegraph-Tape, of 10 which the following is a specification.

The method of making the tape herein shown and described is claimed in the pending application of Patrick B. Delany, 15 filed July 9, 1917, No. 179,509.

As illustrated, Figure 1 shows conventionally the arrangement of parts appropriate for carrying out the invention. Fig. 2 shows the tape lifted clear of the wetting 20 wheel when the signals cease to be received. Fig. 3 is a cross section showing the tape contained within its lifting arm. Fig. 4 shows the tape after the solution has been applied according to our method. Fig. 5 shows a section of the absorbent wick for 25 the wetting wheel; and Fig. 6 shows the wetting wheel in section with the absorbent wick mounted in its periphery. Fig. 7 is a modified form of wetting wheel. Fig. 8 shows means for supplying solution to the 30 tray.

In carrying out our invention we preferably employ a supply reel 1 on which is mounted a roll of dry tape. 2 is a guide wheel vertically adjustable to regulate the contact between the tape 3 and the wetting 35 wheel 4. 5 is a lifting arm having a slotted end 5^a through which the tape passes while 6 is a guide roller tending to keep the tape in 40 alinement between the wetting wheel 4 and the receiver. It will be noted that the lifting arm 5 is supported by a spring attached to an adjusting screw. In this way the tension on the tape while passing over the wheel 4 45 may be very nicely adjusted so that the proper amount of the chemical solution may be applied to the tape. As soon as the feed of the tape is suspended, the arm serves to lift the tape from the wheel. As before 50 stated the guide wheel 2 is vertically adjustable and also serves to regulate the contact between the solution applying wheel and the tape. At 7 we have indicated a receiver contact drum forming connection to the

ground G for the line 8 through the finger 9 55 and the chemical tape 3. 10 and 12 are pulling rollers, suitably rotated.

The tray 13 holds the chemical solution 14. By means of a knob 15 upon the shaft on which wheel 4 is mounted the wheel may be 60 given a turn through the solution to insure saturation at the start of that portion of the tape between the wetting wheel and the solution. This also avoids waste of time and of the tapes. But for this a considerable extent 65 of blank tape would have to precede the perforated signals at the transmitting station in order to allow the saturated tape to arrive at the marking finger 9. At the conclusion of the transmission the roller 12 is 70 lifted from the driven roller 10 automatically as well understood in the art. The tension on the tape thereupon relaxes to permit the lifting arm 5 to raise the tape out of contact with the wetting wheel 4, thus avoiding 75 over saturation and weakening of the tape at that point during temporary inactivity.

The wetting wheel 4 may be formed with a peripheral groove to receive a wick 4^a, as 80 shown in Figs. 5 and 6. Another form is shown in Fig. 7 where a circular piece of felt A is held by screws between two hard rubber disks B, the felt being slightly wider than the disks. 85

The finished tape assumes the form shown in Fig. 4 where 16 designates the surface bearing the chemical solution and 17 the dry or normal surface at each side. 90

Heretofore it has been customary to immerse loosely wound rolls of the tape in the chemical solution, or to draw the tape through the liquid. These methods have not been entirely satisfactory because when freshly treated the tape is frequently too wet 95 and likely to break, while after a few days in storage the tape is apt to become too dry.

Our invention obviates these faults. The tape is drawn over the feed wheel 4 partly immersed in the chemical solution and monitored by the tape as it is drawn over its upper rim. Around this feed wheel is banded the absorbent wick 4^a which carries the solution to the under side of the tape in any quantity desired, the saturation being 105 regulable by increase or decrease of the contact of the tape with the supply wheel. In practice good results are obtained by use of

a wheel about three inches in diameter and one-eighth of an inch in width. The delivered solution, spreading to a width of about one-fourth of an inch, leaves about one-eighth of an inch of dry tape on each side. In this way the strength of the tape is equal to any strain put upon it, breaking is avoided, less solution is required, saturation is always uniform and the effectiveness of 10 electro-chemical action at its highest.

In drawing the tape over the wetting wheel some of the solution is sprayed on the tape by centrifugal force in advance of the contact between the tape and the wheel, 15 thereby facilitating and preventing waste or slopping of solution.

It is advisable to provide means for automatically supplying the chemical solution to the tray 13. An appropriate structure is 20 shown in Fig. 8. The tray 13 is shown communicating with a large container, as a bottle 18. This bottle has an opening in its lower portion in which is a rubber stopper 19 drilled to permit the entrance at an angle 25 of a glass tube 20 having a stop cock 21. A rubber base 22 leads from the tube into tray 13. While the level of solution in 13 covers the end of the hose no flow occurs, but when this level drops and exposes the hose end, 30 an air bubble passes to the container and permits more solution to pass to the tray.

It will be observed that the contact devices 7 and 9 are interposed between the tape-advancing mechanism (10, 12) and the wetting wheel 15. It will also be observed that the treated portion of the tape is arranged centrally thereon and that there are untreated portions on opposite sides of the treated portion. If the treated portion of 40 the tape should be immediately presented to the contact devices there would be too much moisture or liquid on the tape to obtain the best results, but inasmuch as the tape is of absorbent material surplus moisture is absorbed by the marginal portions of the tape 45 before reaching the contact devices.

In the pending application of Patrick B.

Delany and Louis W. Shumaker No. 239,575, filed June 12, 1918, apparatus somewhat similar to that herein shown and described 50 is illustrated, described and claimed. The claims in the present application are confined to certain details of construction which are not claimed in said application of June 12, 1918. 55

We claim as our invention:

1. In an apparatus for treating telegraph tape, means for advancing the tape, a container of chemical solution, a wheel whose periphery is immersed in the solution and 60 which is formed with a groove, and a wick in said groove, said tape passing in contact with the wick and the wick being narrower than the tape.

2. In an apparatus for treating telegraph 65 tape, means for advancing the tape, a container of chemical solution, a wheel whose periphery is immersed in the solution and which is provided with a peripheral portion 70 of absorbent material which is narrower than the tape.

3. In an apparatus for treating telegraph 75 tape, means for advancing the tape, a container of chemical solution, a wetting wheel for the tape operating in said solution and having an absorbent peripheral portion for applying to the middle portion of the under side of the tape a line of solution while the marginal portions are not thus treated and which thus serve to absorb excess moisture 80 from the treated portion of the tape.

4. In an apparatus for treating telegraph 85 tape, means for advancing the tape, a container for a chemical solution, a wheel whose periphery is immersed in the solution and which applies solution to the under side of the tape, means for automatically supplying liquid to said container, and means for revolving said wheel independently of any movement given thereto by the tape. 90

In testimony whereof we have hereunto subscribed our names.

PATRICK B. DELANY,
LOUIS W. SHUMAKER.
